UNITED STATES PATENT OFFICE

2,030,297

CORE CATCHER

John H. Howard, Huntington Park, and Alfred C. Catland, Alhambra, Calif., assignors to Globe Oil Tools Company, Los Nietos, Calif., a corporation of California

Original application August 7, 1933, Serial No. 684,018. Divided and this application February 2, 1934, Serial No. 709,461

8 Claims. (Cl. 255—72)

This invention has to do with a well tool and has particular reference to a core catcher for use in a well core drill. A general object of the invention is to provide a practical, effective core catcher of simplified and improved construction.

5 This application is a division of our application for United States Letters Patent entitled Core drill, Serial No. 684,018, filed August 7, 1933.

An object of this invention is to provide a novel 10 and particularly effective core catcher that is capable of dependably supporting and retaining cores of both hard and soft earth formations, and cores that are broken or shattered.

Another object of the invention is to provide 15 a core catcher of the pivoted dog type that is rotatably mounted in the core drill so that it is free to float, whereby it may be held against rotation through contact with the core during the drilling operation.

20 Another object of the invention is to provide a core catcher embodying replaceable core engaging dogs pivotally mounted in a simple and dependable manner.

Another object of the invention is to provide 25 a core catcher having core engaging dogs which each have two faces or shoulders spaced apart and adapted to cooperate with two seats on the body of the core catcher to dependably support the dogs when they are holding the core.

30 A further object of the invention is to provide a floating or rotatably supported core catcher embodying pivoted core gripping and supporting dogs mounted and arranged so that the outward thrusts to which they are subjected while acting 35 on and supporting the core, are transmitted directly to the bit head or other surrounding part of the core drill.

A further object of the invention is to provide 40 a core catcher including a sectional body, pivoted core engaging dogs and a simple effective means for connecting the sections of the body that is such that the core catcher may be easily and quickly taken apart for repair or for the replacement of its parts.

45 Other objects and features of the invention will be better and more fully understood from the following detailed description of a typical form and application of the invention, throughout which description reference may be had to the 50 accompanying drawing, in which:

Fig. 1 is a side elevation of a core drill carrying or embodying the core catcher of the present invention with the principal parts of the drill and core catcher broken away to appear in longitudinal cross section. Fig. 2 is a top or plan view

of the core catcher apart from the drill, with a portion broken away to appear in horizontal cross section, being a view taken substantially as indicated by line 2—2 on Fig. 3. Fig. 3 is a vertical detailed sectional view of the core catcher taken as indicated by line 3—3 on Fig. 2 and illustrating the dogs in the actuated positions.

5 The core catcher of the present invention may be employed in core drills varying considerably in construction. In the following detailed disclosure of the invention we will describe a typical preferred form of core catcher operating in a core drill of the type fully described and claimed in our co-pending application, mentioned above, and our application for United States Letters 10 Patent entitled Core drill, filed February 2, 1934, Serial No. 709,460. It is to be understood that the invention is not to be construed as limited or restricted to the specific form or application about to be described, but is to be taken as including 15 any features or modifications that may fall within the scope of the claims.

The core drill illustrated in the drawing includes an outer barrel 10 provided at its upper end with a connecting member or sub 16 for 20 facilitating connection of the drill and a well drilling string. A sub 18 is provided on the lower end of the outer barrel 10 and carries a bit head 19. A bit head 11 is screw threaded on the sub 19 and is provided with circumferentially 25 spaced cutting blades 21 for making an annular cut in the earth formation. The bit head 11 is tubular and has an internal annular recess 25. An inner barrel 12 is provided in the drill for receiving the core cut by the bit head 11. The inner barrel 12 has a ring or enlargement 29 on its lower end which is rotatably supported in the recess 25 of the bit head 11. The lower end portion of the enlargement 29 has an internal annular recess 33 which, together with the recess 25 40 of the bit head 11, carries or contains the core catcher. The lower end of the inner barrel 12 is open for the reception of the core while a valve 14 is provided on the upper end of the inner barrel to prevent the downwardly flowing circulation 45 fluid from entering it. The valve 14 is adapted to open to permit the discharge of fluid from the inner barrel 12 as it is displaced by the entering core. The inner barrel 12 is spaced from the interior of the outer barrel 10, providing an annular fluid passage S which communicates at its lower end with ports 60 in the enlargement 29. The ports 60 communicate with discharge passages 62 in the bit head 11 through an annular recess provided in the interior of the bit head.

The core catcher provided by the invention includes, generally, a sectional body A rotatably supported in the core drill, pivoted core engaging dogs B on the body A, and means C for operating the dogs B.

The core catcher body A is adapted to be rotatably arranged in the core passing or receiving opening of the core drill in a position where its dogs B may have the desired engagement with the core. In the particular core drill illustrated in the drawing the body A is rotatably supported in the lower portion of the bit head recess 25 and extends upwardly into the recess 33 in the inner barrel enlargement 29. The body A is tubular or annular and has limited longitudinal movement in the core drill. The lower wall of the recess 25 limits the downward movement of the body A while the upper wall of the recess 33 limits the upward movement of the body A. In accordance with the invention the body A is sectional comprising two sections or rings 35 and 36. The rings 35 and 36 are telescoped one within the other, the ring 35 being the outer ring and surrounding the major portion of the ring 36. The body sections or rings 35 and 36 have opposing contacting faces 37. The faces 37 are preferably inclined with respect to the longitudinal axis of the body. The upper ends of the rings 35 and 36 may be flush to provide the body A with a flat upper end. The inner ring 36 may project downwardly beyond the lower end of the outer ring 35, providing the body A with a reduced lower end portion to seat or operate in the portion of the bit head recess 25 below an inclined upwardly facing shoulder 27 on the wall of the recess 25. The opening 38 in the body A is in vertical register and alignment with the core receiving opening 34 of the bit head 11.

In accordance with the invention an annular space or groove 43 is provided between the contacting bearing faces 37 of the rings 35 and 36. In the particular structure illustrated in the drawing the space or groove 43 is formed in the inner ring 36 and is closed at its outer side by the outer ring 35. The inner wall of the groove 43 may be curved while the upper and lower walls of the groove may be flat and join the cylindrical surface 37 of the outer ring 35. The core catcher body A is provided with spaced slots or openings for carrying the dogs B. Circumferentially spaced vertical slots 39 are provided in the inner ring 36 and vertical openings or slots 40 are provided in the outer ring 35 to join or communicate with the slots 39. The slots 39 extend downwardly from the upper end of the ring 36 and their lower walls form upwardly facing seats or shoulders 51. The openings or slots 40 in the outer ring 35 communicate with the lower portions of the slots 39 and their upper ends present downwardly facing shoulders 52.

The dogs B are pivotally mounted in the openings or slots of the body A and are provided to grip and support the core cut by the bit head 11. The means for pivotally supporting the core engaging dogs B is a feature of the invention and includes pins 42 extending through transverse openings in the dogs 41. The pins 42 project from the opposite sides of the dogs B and their projecting end portions extend into the groove 43 which intersects the slots 39. The projecting end portions of the dog supporting pins 42 are tapered or flattened as at 47 to cooperate with the outer vertical wall of the groove 43 to positively prevent rotation of the pins. The flattened or tapered portions of the pins 42 at 47, in addition to hold-

ing the pins against rotation tend to prevent the pins from shifting longitudinally.

It is an important feature of the invention that the rings 35 and 36 of the body A are securely, detachably connected together in a manner to positively prevent shifting or displacement of the dog carrying pins 42. The means for connecting the sections or rings 35 and 36 of the body A is simple and permits the easy disconnection of the rings to provide for the repair or replacement of the various parts of the core catcher. The means connecting the body rings 35 and 36 comprises rivets 44 which extend through radial openings in the rings. The rivets 44 intersect or pass through the groove 43 adjacent the ends of the dog carrying pins 42 and thus positively prevent excessive or undesirable longitudinal movement of the pins. The heads or ends of the rivets 44 are preferably flush with the inner and outer surfaces of the body A as illustrated throughout the drawing. It will be apparent how the rivets 44 securely and dependably connect the body rings 35 and 36 and prevent shifting of the pins 42. When it becomes desirable or necessary to disconnect the rings 35 and 36 for the replacement of the dogs B or for other reasons the rivets 44 may be easily and quickly drilled out to free the rings 35 and 36 for disconnection from one another.

The core gripping and supporting dogs B project through the openings or slots 40 for the purpose to be subsequently described, and are adapted to project into the core passing opening 38 of the body A to engage the core. The upper and lower sides of the dogs B converge outwardly to comparatively sharp edges 46. The dogs B are shaped and proportioned so that they are adapted to be entirely received within the slots 39 with the exception of small parts which may extend into the enlargement 29 of the inner barrel 12. The slots 39 in fully receiving the dogs B allow the dogs 40 to pivot upwardly and outwardly to positions where they are entirely clear of the core passing opening 38 of the body. The opposite vertical sides of the dogs B are preferably flat to have good bearing engagement with the side walls of the slots 39 when the dogs B are subjected to turning or twisting forces through their engagement with the core.

In accordance with the invention the dogs B are of different lengths whereby certain of the dogs are capable of dependably supporting full sized cores of hard formations while other dogs are adapted to support undersized cores and broken cores. One or more comparatively short dogs B¹ are provided to grip and retain full sized cores of hard earth formations. The relatively short dogs B¹ have effective angles of attack or engagement with cores of hard earth formations which are usually full sized so that it is practically impossible for a large core or hard core of full diameter to slip through the core catcher when the drill is raised. One or more dogs B² of medium or intermediate length are provided for gripping and supporting cores of soft or relatively soft earth formations which are quite frequently undersized in diameter. The dogs B² of medium length are capable of effectively gripping and supporting cores that might not be properly engaged or contacted by the shorter dogs B¹. One or more comparatively long dogs B³ are provided for supporting and catching cores that are badly broken or shattered. The dogs B³ are adapted to project substantial distances into the opening 38 to prevent pieces or fragments of badly broken cores from passing through the core catcher as 75

the drill is raised. In accordance with the broader aspects of the invention there may be any desired or practical number of dogs B provided on the body A. In the particular case illustrated in the drawing there are two diametrically opposite dogs B¹, two diametrically opposite dogs B² and two diametrically opposite dogs B³.

The means C for operating the dogs B into engagement with the core normally yieldingly urges the dogs against the core and acts to positively pivot the dogs into the core upon upward movement of the drill. The dog actuating means C includes springs 49 for yieldingly urging the dogs against the core and cam parts 54 on the dogs for cooperating with a part or shoulder on the core drill to positively actuate the dogs into the core when the drill is raised. A notch 48 is provided in the outer or pivoted end portion of each dog B to carry a spring 49. The notches 48 intersect the openings passing the pins 42 and the springs 49 surround the pins where they pass through the notches. The springs 49 are helical torsional springs and each spring has an end bearing against a body shoulder 31 and an end bearing against the inner wall of a notch 48. The springs 49 are under torsional strains to normally urge the core engaging dogs B downwardly and outwardly into the body opening 38. The spring carrying notches 48 are spaced between the opposite vertical sides of the dogs B so that both sides of each dog present an extensive surface for bearing against a side wall of a slot 39. The springs 49 in urging the dogs B downwardly and inwardly into the opening 38 yieldingly hold the dogs in contact with the core during the drilling operation to resist turning of the core catcher. The body A in being rotatably supported in the drill as described above, has little tendency to rotate with the drill so that the spring urged engagement of the dogs B with the core may hold the core catcher against turning without subjecting the dogs or other parts to excessive wear or strains.

The body A is arranged for limited longitudinal movement in the core drill and the cam parts 54 are provided to cooperate with a part of the drill to forcibly actuate the dogs B against or into the core when the drill is raised or moved upwardly relative to the body A. The cam parts 54 are provided on the outer portions of the dogs B which extend into the openings or slots 40. The cam projections or parts 54 protrude through the slots 40 so as to engage the shoulder 27 in the bit head 11. During the drilling operation the springs 49 yieldingly hold the dogs B in engagement with the core, thereby resisting downward movement of the core catcher with respect to the core so that the body A is held upwardly in the recesses 25 and 33. This spaces the cam parts 54 above the shoulder 27. After a core of sufficient length has been obtained and the drill is raised to recover the core, the spring urged engagement of the dogs B with the core resists upward movement of the core catcher so that the shoulder 27 is brought into contact with the cam parts 54. The upwardly moving shoulder 27 engaging the cam parts 54 forcibly pivots the dogs B downwardly and inwardly into the opening 38 in the body A to come into effective gripping and supporting engagement with the core. The camming engagement of the cam parts 54 with the shoulder 27 aids the springs 49 in their actuation of the dogs B and insures the positive inward pivoting of the dogs.

The invention includes means for supporting

the dogs B against further downward movement when in the fully actuated positions. Each dog B is provided with a flat surface 50 adapted to cooperate with a seat 51 and a flat surface 53 adapted to cooperate with a shoulder 52. The surfaces 50 and 53 are located so that they come into engagement with the body seats 51 and 52 when the dogs reach their fully extended or operated positions. The stop faces 50 and 53 are located at the opposite sides of the pivotal axes of the dogs and are effective in positively limiting further downward pivoting of the dogs B when in bearing engagement with the seats 51 and 52. In addition to the support offered the dogs B by the engagement of the faces 50 and 53 with the body seats, the cam parts 54 or the protruding parts of the dogs B engage the shoulder 27 of the drill to support the dogs against outward thrusts. The dog supporting pins 42 are thus relieved of severe strains when the dogs B are operated to break the core free from the formation and when the dogs are carrying the core.

It is believed that the utility and practicability of the core catcher provided by this invention will be readily apparent from the foregoing detailed description. During the drilling operation, that is, when the core drill is operated on the lower end of a rotating drilling string, the bit head 11 makes an annular cut to form a core which is received by the opening 34 and the inner barrel 12. The springs 49 yieldingly urge the dogs B inwardly against the core as the drill is rotated and fed downwardly, and the yielding contact of the dogs with the core may hold the core catcher against rotation. Further, the engagement of the dogs B with the core resists downward movement of the core catcher so that the body A of the core catcher may remain in the upper portion of the recess 25 and the recess 33 during drilling. The slots 39 are such that they are capable of allowing the dogs B to move to their fully out or unactuated positions where they allow the free passage of a large core through the core catcher. The cam parts 54 are spaced vertically out of engagement with the shoulder 27 when the core catcher body A is held in its up position, as described above, so that they have no tendency to force the dogs B into the core.

When the drill is raised to actuate the dogs B and to remove the drill and the core from the well, the engagement of the spring urged dogs B with the core tends to hold the body A against upward movement, so that the shoulder 27 is brought into contact with the cam parts 54. The engagement of the shoulder 27 with the cam parts 54 pivots the dogs B into firm positive engagement with the core and provides for the actuation of the dogs B to their fully operated positions. The dogs B in being of different lengths are adapted to engage and support undersized and broken cores as well as full sized cores of hard earth formations. When in supporting engagement with the core the dogs B are in the positions where their faces 50 and 53 cooperate with the seats 51 and 52 so that the pins 42 are relieved of severe strains. The opposite vertical ends of the dogs B may engage the vertical walls of the slots 39 when the dogs are subjected to turning or twisting forces and the provision of the springs 49 in the notches 48 does not complicate or weaken the pivotal mountings of the dogs. The rivets 44 effectively connect the rings or sections 35 and 36 of the body A and operate to prevent longitudinal shifting or displacement of the dog carrying pins 42. If it be

- comes desirable or necessary to take the core catcher apart to permit the replacement of parts the rivets 44 may be easily and quickly drilled out to allow the rings 35 and 36 to be slid apart.
- 5 Separating of the rings 35 and 36 disconnects the dogs B from the body A. The core catcher may be quickly taken apart and reassembled.
- Having described only a typical form and application of our invention, we do not wish to be limited or restricted to the specific form and application herein described, but wish it to be considered as including any variations or modifications that may appear to those skilled in the art or fall within the scope of the following 10 claims:

Having described our invention, we claim:

1. A core catcher including a body comprising two rings in telescopic relation, there being an annular groove between the rings and slots in 20 the body intersecting the groove, core engaging dogs extending into the slots, pins pivotally carrying the dogs and having their end portions supported in the groove, and connecting members extending through openings in the rings to connect the rings and intersecting the recess to prevent movement of the pins.
2. A core catcher including a body comprising two rings in telescopic relation, there being an annular groove between the rings and slots in 30 the body intersecting the groove, core engaging dogs extending into the slots, pins pivotally carrying the dogs and having their end portions supported in the groove, the pins having substantially flat parts engaging the wall of the groove 35 to prevent rotation of the pins, and means detachably connecting the rings.
3. A core catcher including a body and a plurality of circumferentially spaced rigid core engaging dogs pivotally carried by the body in a 40 common horizontal plane, the dogs being different lengths.
4. A core catcher including a sectional annular body, a plurality of core engaging dogs, independent pins pivotally supporting the dogs, the

pins being removably carried in an opening between sections of the body, and means detachably connecting the sections of the body and preventing movement of the pins in the opening.

5. A core catcher including a sectional annular body, a plurality of core engaging dogs, pins pivotally supporting the dogs, the pins being removably carried by the body, and rivets extending through openings in the sections of the body adjacent the ends of the pins to connect the sections and to prevent movement of the pins.

6. A core catcher including a body having an opening for passing a core and a plurality of circumferentially spaced rigid dogs pivoted on the body in a common horizontal plane for engaging 15 the core, some of the dogs being adapted to project a relatively short distance into the opening to bite into a core of large diameter, other dogs being adapted to project a greater distance into the opening to bite into a core of smaller diameter, the short dogs being spaced between the longer dogs.

7. A core catcher including a body having an opening for passing a core and rigid dogs pivotally carried by the body at circumferentially spaced 25 points in a common plane for engaging the core, one dog being adapted to project a relatively short distance into the opening to bite into a core of large diameter, another dog being adapted to project a greater distance into the opening 30 to bite into a core of smaller diameter, and a third dog being adapted to project a still greater distance into the opening to catch a broken core.

8. A core catcher including a body having an opening for passing a core, the body comprising 35 separable sections, there being a groove between contacting parts of the sections, a dog, a removable pin carrying the dog for pivotal movement and supported in the groove, and removable members connecting the sections and intersecting the 40 groove to prevent displacement of the pin.

JOHN H. HOWARD.
ALFRED C. CATLAND.
